UNITED STATES PATENT OFFICE.

GRANT HAMMOND, OF HARTFORD, CONNECTICUT, ASSIGNEE OF ONE-THIRD TO ALVA C. WASHBURN, OF PITTSFIELD, MASSACHUSETTS, AND ONE-THIRD TO FREDERICK G. CRANE, OF DALTON, MASSACHUSETTS.

FIREARM.

1,138,379.

Specification of Letters Patent.

Patented May 4, 1915.

Application filed February 3, 1914. Serial No. 816,152.

To all whom it may concern:

Be it known that I, GRANT HAMMOND, a citizen of the United States, and a resident of Hartford, in the county of Hartford and 5 State of Connecticut, have invented a new and Improved Firearm, of which the following is a specification.

My invention relates more especially to that class of firearms that are commonly discharged from the hand as the only support, 10 and an object of my invention, among others, is the production of a firearm that shall be extremely cheap to manufacture, one that shall be compact in the arrangement of its 15 several parts, and one that shall be effective in operation.

One form of firearm or pistol embodying my invention, and in the construction and use of which the objects herein set out, as 20 well as others, may be attained, is illustrated in the accompanying drawings, in which—

Figure 1 is a view in side elevation of a firearm embodying my invention, the handle being cut away in lengthwise central section. 25 Fig. 2 is a detail side view of my improved firearm, with parts broken away to show construction. Fig. 3 is a view in cross section through the handle on plane denoted by dotted line 3—3 of Fig. 2. Fig. 4 is a detail 30 view of the back piece.

In the accompanying drawings the numeral 5 indicates the handle of my improved firearm, 6 the receiver, 7 the barrel secured to the receiver, 8 the trigger guard, 9 the 35 trigger, and 10 the breech-bolt, all of which may embody any ordinary and well known construction and which, except in combination with other members, form no part of my present invention, and for this reason 40 further and detailed description is omitted herein.

The handle 5 is preferably composed of a piece of wrought metal, in which a groove is cut from the back to a point closely approaching the front part thereof, leaving a comparatively thin front wall 11. The front or deeper part of this groove constitutes a magazine chamber 12 and the opening or mouth into the groove receives a back piece 50 13 that, together with the edges of the comparatively thin side pieces, forms the back of the handle. Aside from the breech-bolt the greater part of the firing mechanism is

located upon this back piece. This back piece has a hole extending from its lower 55 end into a slot at its upper end, said hole forming a well 14 within which the main or hammer spring and the breech-bolt actuating spring are located. The lower end of the well is closed by a plug 15 and the slot 60 above mentioned forms a sear and hammer chamber 16 within which the sear 17 and hammer 18 are pivotally mounted, the sear in position to be operated by a connection from the trigger, and the hammer to properly contact with the firing pin 19 in the breech-bolt.

A hammer actuating rod 20 extends from a head 21 located within the lower end of a main spring sleeve 22 resting with its lower 70 end against the plug 15, the opposite end of this sleeve having a flange 23 resting against a shoulder 24 in the well 14. The end of the hammer actuating rod has a hook 25 that engages a pin upon the hammer, as 75 clearly shown in Fig. 1 of the drawing. This actuating rod and its connections forms subject matter in my co-pending application, S. No. 825,248, filed March 17, 1914, and no claim is therefore made to it herein. The 80 head 21 is secured in place in any suitable manner, as by means of a pin passed through the sleeve and head. A hammer or main spring 40 is located within said sleeve, thrusting with its lower end against the head 85 21 and with its upper end against a shoulder 41 in this end of the sleeve, the force of the spring being thus exerted to draw the hammer into engagement with the firing pin 19, the hammer actuating rod extending 90 through said spring and out at the upper end of said sleeve.

A breech-bolt actuating sleeve 26 nicely fits the sleeve 22 so that it may freely slide thereon, this sleeve having a head 27 fitting 95 within the well 14. A breech-bolt actuating spring 28 surrounds the sleeve 26 and thrusts with one end against the plug 15 and with its opposite end against a shoulder formed by the head 27, a pin 29 projecting from 100 said head into engagement with a notch in one arm of a pivotally mounted breech-bolt actuating lever 30. This breech-bolt actuating lever is engaged with the breech-bolt between the lugs 31—32, so that backward 105 movement of the breech-bolt, that is effected

by the backward movement of the casing 33 in the usual manner, will cause the lever to be swung on its pivot against the tension of the breech-bolt actuating spring 28. In this 5 backward movement of said lever a cam lug 34 on the side of the lever engages a cam 35 on a sear actuating bar 36, slidably mounted in the frame and with its front end resting against the trigger 9, and its rear end shaped 10 and positioned to engage a sear lug 37 projecting from the side of the sear 17. This engagement of the cam lug 34 with the cam 35 will cause the actuating bar 36 to be released from engagement with the sear, even 15 though conditions might cause the trigger 9 to be retained in its backward position, and the sear is thus enabled to resume its normal position to engage the notches in the hammer and a repeated unintentional discharge 20 of the firearm is thus prevented. A spring 25 pressed plunger 38 has a beveled end arranged to engage a cross piece 39 at the front of the sear actuating bar 36, the bar being thus held at the forward limit of its play and against the trigger 9. This action of the plunger also retains the back end of the bar in position to normally engage the sear.

The sear has a groove 43 extending from its rear edge through which the actuating 30 rod 20 extends into a groove in the hammer where it engages a pin secured to the hammer. A magazine catch 42 may be employed to hold the magazine in place but as this forms no part of my present invention 35 further description of this, as well as of other minor parts, is omitted herein.

While I have shown and described herein a satisfactory arrangement of parts embodying my invention, these may be changed to 40 a greater or lesser degree and yet be within the spirit and intent of the invention.

I claim—

1. A firing mechanism for a firearm including a breech-bolt, a member to actuate 45 the breech-bolt, a hammer, a sear, means for actuating the sear, and means upon the breech-bolt actuating member to disengage the sear and its actuating means.

2. A firing mechanism for a firearm including a breech-bolt, a breech-bolt actuating lever, a hammer, a sear, means for actuating the sear, and means upon the breech-bolt actuating lever to engage the sear actuating means to disengage it from the sear.

55 3. A firing mechanism for a firearm including a breech-bolt, a breech-bolt actuating lever, a hammer, a sear, a sear actuating bar, means for operating said bar, and a shoulder upon said lever to engage said bar 60 to disengage it from said sear.

4. A firing mechanism for a firearm including a breech-bolt, a breech-bolt actuating lever, means for actuating said lever, a trigger, a sear, a sear actuating bar, a hammer, means for engaging the sear and ham-

mer, and means upon said lever acting upon said bar to permit engagement of the sear and hammer during the opening movement of the breech bolt.

5. A firing mechanism for a firearm including a breech-bolt, a breech-bolt actuating lever, means for actuating said lever, a trigger, a sear, a hammer, a connecting member for transmitting movement of the trigger to the sear, and means upon said breech-bolt actuating lever to disengage said connecting member from the sear during the firing operation.

6. A firing mechanism for a firearm including a breech-bolt, a breech-bolt actuating lever, means for actuating said lever, a trigger, a hammer, a sear, a connecting member for transmitting movement of the trigger to the sear, and means upon said breech-bolt actuating lever to disengage said connecting member from the sear during the backward movement of the breech-bolt.

7. A firing mechanism for a firearm including a breech-bolt, a breech-bolt actuating lever, means for actuating said lever, a cam lug upon said lever, a trigger, a hammer, a sear, and a sear actuating bar having a cam to be engaged by said lug to disengage 85 said bar from the sear.

8. A firing mechanism for a firearm including a frame, a hammer, a hammer actuating rod secured at one end to the hammer and having a head at its opposite end, a sleeve removably located within the frame and having an opening extending from one 100 end to a point near the opposite end, and a small opening extending through said opposite end, a spring removably seated around the edge of said small opening in the sleeve and with its opposite end thrusting 105 against said head, a sear, and means for operating the sear.

9. A firing mechanism for a firearm including a hammer, a hammer actuating rod connected with the hammer at one end and having a head at its opposite end, a hammer spring surrounding said rod and thrusting with one end against said head, means for receiving thrust of the opposite end of the spring, a breech-bolt, a breech-bolt actuating member, a breech-bolt actuating spring surrounding said hammer spring, connections between the breech-bolt actuating spring and breech-bolt actuating member, a sear in engagement with the hammer, 120 and means for operating the sear.

10. A firing mechanism for a firearm including a breech-bolt, a breech-bolt actuating member, a hammer, a sear, means for actuating the sear, a hammer actuating rod connected with the hammer at one end, a hammer spring surrounding said rod and arranged to exert thrust thereupon, a breech-bolt actuating spring surrounding said hammer spring, a sleeve located between the 125

- breech-bolt actuating spring and hammer spring, and a connection between the breech-bolt actuating spring and breech-bolt actuating member.
- 5 11. A firing mechanism for a firearm including a breech-bolt, a breech-bolt actuating member, a hammer, a sear coacting with the hammer, a trigger to operate the sear, a hammer actuating rod, a sleeve surrounding said rod, a spring located within the sleeve to exert pressure upon the rod, a second sleeve surrounding the first sleeve and slideable thereon, a breech-bolt actuating spring surrounding the second sleeve, and connections between said sleeve and breech-bolt actuating member. 70
- 10 12. A firearm including a handle having a groove therein, a back piece closing said groove and having a hole extending lengthwise therein, a breech-bolt, a breech-bolt actuating member, a breech-bolt actuating sleeve slidably mounted within said hole, a breech-bolt actuating spring surrounding said sleeve, a main spring sleeve located within the breech-bolt actuating sleeve, a main spring located within the main spring sleeve, a hammer actuating rod extending through said main spring and having a head to receive the thrust thereof, said rod being connected with a hammer, the hammer mounted on the back piece, a sear mounted on the back piece, and a trigger to operate the sear. 80
- 15 13. A firing mechanism for a firearm including a hammer, a hammer actuating rod connected with the hammer at one end and having a head at its opposite end, a hammer spring surrounding said rod and thrusting with one end against said head, means for receiving thrust of the opposite end of the spring, a breech-bolt, a breech-bolt actuating member, a breech-bolt actuating spring surrounding said hammer spring, connections between the breech-bolt actuating spring and breech-bolt actuating member, and means for controlling the movement of the hammer. 90
- 20 14. A firing mechanism for a firearm including a hammer, means for actuating the hammer, a breech-bolt, a breech-bolt actuating member, a frame containing said firing mechanism, a sleeve slidably mounted in the frame, a breech-bolt actuating spring in engagement with said sleeve, and a connection between the breech-bolt actuating member and said sleeve. 100
- 25 15. A firing mechanism for a firearm including a frame, a hammer, means for actuating the hammer, a breech-bolt, a breech-bolt actuating member, a sleeve removably secured within the frame, a breech-bolt actuating sleeve slidably mounted upon said removable sleeve, and connections between the breech-bolt actuating sleeve and said breech-bolt actuating member. 105
- 30 16. A firing mechanism for a firearm in- cluding a frame, a hammer, a sleeve, a spring located within said sleeve, a hammer actuating rod connected with the hammer, and with said spring, a breech-bolt, a breech-bolt actuating member, and a spring surrounding said sleeve and operatively connected with the breech-bolt actuating member. 110
- 35 17. A firearm including a frame, a hammer, a sleeve removably located in the frame, a spring located within said sleeve, a hammer actuating rod connected with said spring and hammer, a breech-bolt, a breech-bolt actuating member, a breech-bolt actuating sleeve connected with said member and surrounding said hammer spring, and a breech-bolt actuating spring exerting thrust upon said breech-bolt actuating sleeve. 120
- 40 18. A firearm including a frame having a hole therein, a hammer, a breech-bolt, a hammer spring sleeve and a breech-bolt actuating sleeve slidably mounted one upon the other and removable as a unit from said hole, a hammer spring and a breech-bolt actuating spring each having a bearing within one of said sleeves, a connection between the hammer and hammer spring, and a connection between the breech-bolt and breech-bolt actuating spring. 125
- 45 19. A firearm including a frame, a hammer mounted in the frame, a breech-bolt, a hammer spring sleeve and a breech-bolt actuating sleeve mounted one within the other, a hammer spring and a breech-bolt actuating spring each having a bearing within one of said sleeves, said sleeves and springs being removably secured as a unit within the frame, a connection between the hammer spring and hammer, and a connection between the breech-bolt actuating spring and breech-bolt. 130
- 50 20. A firing mechanism for a firearm including a breech-bolt, a member to actuate the breech-bolt, a hammer, means operatively connected with the hammer to control its movement, and means upon the breech-bolt actuating member to render said hammer controlling means inoperative during the opening movement of the breech bolt. 135
- 55 21. A firing mechanism for a firearm including a breech-bolt, a member to actuate the breech-bolt, a hammer, a sear, means for actuating the sear, means to cause engagement of the sear and hammer, and means influenced by movement of the breech-bolt actuating lever to permit engagement of the sear and hammer during the backward movement of the breech-bolt. 140
- 60 22. A firing mechanism for a firearm including a breech-bolt, a member to actuate the breech-bolt, a hammer, a sear, means to cause engagement of the hammer and sear, means for actuating the sear, and means upon the breech-bolt actuating member to engage the sear actuating means during the backward movement of the breech-bolt. 145

23. A firing mechanism for a firearm including a breech-bolt, a member to actuate the breech-bolt, a hammer, a sear, means to cause engagement of the hammer and sear, 5 means for actuating the sear, and means upon the breech-bolt actuating member to render said sear actuating means inoperative during the backward movement of the breech-bolt.

GRANT HAMMOND.
